UNITED STATES PATENT OFFICE.

ERNST VOGEL, OF BERLIN, GERMANY.

METHOD OF MAKING OVERLAYS.

SPECIFICATION forming part of Letters Patent No. 664,909, dated January 1, 1901.

Application filed May 14, 1900. Serial No. 16,672. (No specimens.)

To all whom it may concern:

Be it known that I, ERNST VOGEL, chemical engineer, a subject of the King of Prussia, German Emperor, residing at No. 240 and 241 5 Friedrichstrasse, in the city of Berlin, in the Kingdom of Prussia, German Empire, have invented a new and useful Improved Method 10 of Overlaying to be Used in Printing-Presses, of which the following is a specification.

10 In carrying my invention into effect I first produce an impression or copy of a printer's cliché (woodcut, linear etching, autotype, or the like) upon a transparent medium, such as paper gelatin, celluloid, or the like. The 15 positive thus obtained is by aid of light copied and developed upon a copper, brass, zinc, or other metal plate, or, if desired, upon stone, in just the same manner as is made use of in the manufacture of high etchings 20 or in the art of aerography, respectively, and also the same sensitive substances—such as asphalt, chrome - albumen, chrome - gum, chrome-gelatin, chrome-glue, or, if desired, mixtures of such substances—are employed.

25 In the drawings, Figure 1 represents conventionally a printer's cliché or engraving having lines in relief. Fig. 2 represents an impression taken therefrom upon a sheet of transparent celluloid. Fig. 3 represents a 30 negative taken from the imprinted celluloid sheet upon a plate of metal or other material. Fig. 4 is the same metal plate after it has been etched by the action of acids; and Fig. 5 represents a sheet of paper intended 35 for "overlay" in printing-presses which has taken up lines of gelatin or other substance from the previously-filled depressed lines of the metal plate.

As indicated above, an impression is first 40 taken from the cliché A upon a sheet of celluloid or other suitable transparent medium B, the raised lines *a* of the cliché being reproduced in black lines *b* on the sheet of celluloid. This impression upon the celluloid 45 sheet is copied upon a metal or other suitable plate C, covered with sensitive material, by exposure to light, the printed lines *b* of the celluloid sheet being represented in this instance by blank spaces *c* on the negative thus 50 taken and the transparent interstitial spaces *b'* by black lines *c'*, the latter indicating the

acid-resisting surfaces or lines. There results thus a negative copy—that is to say, the metal or the stone is free or uncovered at all those places which correspond to the black 55 parts of the positive, whereas the other places, that correspond to the transparent parts of the positive, are covered by the remaining layer of asphalt, chrome-albumen, chrome-gum, chrome-gelatin, chrome-glue, 60 &c., the respective substance having become insoluble in consequence of the action of the light.

Instead of copying directly upon metal or stone the positive may also be copied upon 65 photolithographic paper or pigment-paper, and the copy may then be transferred upon the metal or stone and developed in known manner.

When the metal plate or stone plate, after 70 having been prepared in the aforescribed way, is introduced into a solution—such as an acid, ferric chlorid, or the like—which is capable of dissolving the respective metal, then the respective solution can exert such 75 an action only at those places of the metal or stone which are free of the above-mentioned layer, because at all the other places the solution is prevented from such action by the insoluble parts of said layer. There is thus 80 obtained a plate D in relief, in which, contrary to an ordinary printing-cliché, those parts *d*, which correspond to the black places of the positive, appear in cavetto, whereas the other parts *d'*, that correspond to the light 85 places of the positive, appear in relief. This relief is the deeper the longer the etching medium has been allowed to act upon the plate. Molten gelatin is now poured over the etched plate, and a sheet of paper or other 90 pliable medium E is placed thereon and the whole subjected to a moderate pressure in a press. After the gelatin has stiffened, the sheet may be taken off the plate and dried, the gelatin from the depressed lines of the 95 plate adhering to it and forming relief lines *e*, corresponding to the relief lines of the original cut or cliché, and adapting the sheet to serve as overlay in a printing-press.

The gelatin may be replaced by celluloid, 100 papier-mâché, caoutchouc, gutta-percha, or another suited material, and, if necessary,

heat may be applied to facilitate the impregnation of the material into the cavities of the printing-plate.

Having now described my invention, what I desire to secure by a patent of the United States is—

The method of producing overlays for use in printing-presses, consisting in first taking an impression from the cut or cliché on a transparent sheet, then producing a negative from said sheet upon the sensitized surface of a suitable plate, etching said plate by the action of suitable acids, covering the

etched surface with melted gelatin, placing a pliable sheet thereon, and subjecting the whole to the action of a press, until the gelatin has stiffened, then removing said sheet with the gelatin adhering thereto in relief lines, and drying it.

In witness whereof I have hereunto set my hand in presence of two witnesses.

ERNST VOGEL.
